CEMENTER FOR PLATFORM SOLE AND
WEDGE HEEL UNITS

Wilbur L. MacKenzie, Beverly, Mass., assignor to
United Shoe Machinery Corporation, Flemington, N. J., a corporation of New Jersey

Application August 14, 1941, Serial No. 406,763

6 Claims. (Cl. 12—80)

This invention relates to coating machines for shoe parts and is herein illustrated as embodied in a machine for applying a marginal band of cement to a combined platform sole and wedge heel unit.

Some shoes are provided with an intermediate or cushion sole which is frequently called a platform sole. Other shoes have been provided with so-called wedge heels extending from the back of the shoe to approximately the ball line. In other cases, these two parts have been combined into a single unit having the general shape of a sole but differing in thickness from front to rear by two or three inches. The foreparts of such units are frequently of felt and hence very flexible. Sometimes, the tread surface of such units is substantially flat and the attaching face is steeply curved, while in others the attaching face is more nearly flat and the surface beneath the instep is curved sharply so that the unit gives the effect of a sole having a modified Louis heel. It is common practice to apply a band of cement around the margin of both the top and the bottom surfaces of most of such units and in many cases one surface overhangs the other so that gaging must be done by reference to the edge of the very surface which is to be coated. Those machines which are commonly employed for applying a marginal band of cement to soles are incapable of handling work pieces of this type because of the wide separation which is required between the supporting roll and the applying member when working at the heel end. Furthermore, such machines gage the work by a device which is located in substantially fixed relation to the work-supporting roll and moves up and down with that support. Such a gaging device is impractical for the very thick units mentioned above both because of the overhang already noted and because, if the gage is supported on a swinging arm which carries the work support, then, the relation of the upper corner of the work to the applying member varies radically as the relatively short arm is depressed, and it is impossible to apply a marginal band in the desired position upon the upper surface of a thick portion of the work.

The object of this invention is to provide an improved coating machine in which the work may be fed without excessive attention upon the part of the operator and in which the correct positioning of the marginal band of coating material to be applied may be easily effected in spite of wide variation in the forms of the work pieces.

The gaging problem has here been solved, in accordance with a feature of the invention, by providing a driven gage roll occupying a fixed relation to a depending applying member which, in the illustrated machine, is a yieldable nozzle. Conveniently, this feature may be embodied in the machine for cementing the bottoms of shoes for the attachment of soles which is disclosed in Letters Patent of the United States No. 2,100,341, granted November 30, 1937, upon an application filed in my name. In that machine, the depending nozzle is carried upon a substantially horizontal arm pivoted to allow heightwise movement of the nozzle and, in order that the gage roll may be supported on the arm and may be driven regardless of its heightwise position, there has been employed, as herein illustrated, a drive shaft provided with universal joints so that there is no interference with the imparted driving movement when the nozzle-carrying arm is lifted. To accommodate various heights of the wedge heel portions of the work, and as herein illustrated, the work is upheld in engagement with the depending coating member by a supporting roll mounted in a carrier arranged for up-and-down movement. The feeding of the work is facilitated, too, by driving this supporting roll through a shaft containing universal joints so that it may be positively rotated regardless of its heightwise position. The variations in heightwise position of this supporting roll are considerable, as noted above. Furthermore, the illustrated work-supporting roll is held upwardly with a substantially uniform tension which is conveniently provided by means of a device of the clock-spring type.

These and other features of the invention will best be understood from a consideration of the following specification taken in connection with the accompanying drawings, in which

Fig. 1 is a side elevation of the machine with a side cover removed;

Fig. 2 is an angular view upon a larger scale showing a shoe unit presented to the end of the nozzle and resting against the gage roll and on the supporting roll;

Fig. 3 is a fragmentary view partly in section of a clock-spring tensioning device used to lift the work-supporting roll; and

Figs. 4 and 5 illustrate platform sole and wedge heel units of the more extreme types.

The working parts of the machine are mounted in a hollow frame 10 supported upon a pedestal 12. The upper part of the frame comprises a back plate 14, and many of the working parts

of the machine are mounted upon this back plate and are retained thereon by a cover plate 16 which is held in fixed spaced relation to the plate 14 by a number of shoulder bolts such as those at 18 and 20. At the top of the machine, a tiltable arm 22 has a depending portion which is pivoted on a cross stud 24, and the arm is urged counterclockwise, as viewed in Fig. 1, by a spring 26 acting against a fixed abutment 28 and depressing the arm, when the machine is in use, to a limit determined by the engagement of a stop screw 30 with a ledge 32.

The particular coating-applying member illustrated herein is an extruding nozzle 34 of the articulated type and may be constructed as illustrated in Letters Patent of the United States No. 2,177,666, granted October 31, 1939, upon an application of W. L. MacKenzie et al. This nozzle is made up of a series of applying members 36 (Fig. 2) which are upwardly yieldable against the tension of springs 38 and which have outlet passages fed with coating material through capillary tubes 40. This nozzle which is adjustably supported upon the arm 22 is provided with coating material under pressure, such as cement, from a tank 42, and the cement is delivered to the nozzle by means of a pump 44 actuated from a drive shaft 46 and communicating with a nozzle 34 through a flexible hose 48. A valve 50 controls the outflow from the nozzle and this valve is operated through a jointed rod 52 by means of a rearwardly extending lever 54 which is connected through a rod 56, a two-arm lever 58, and a slotted link 60 to a treadle rod 62. The two-arm lever 58 is upheld by means of a spring 64 which, when the treadle (not shown) is released, operates to close the valve 50 by moving the lever 54 against a stop screw 66. At the same time that this is done, the nozzle-carrying arm 22 is lifted by the action of coating levers 68 and 70 and in this the spring 64 is assisted by a treadle spring (not shown) which urges the treadle rod 62 upwardly. The lever 68, pivoted on the frame, is joined at its right end to the upper end of the treadle rod and at its left end has a pin camming against the long arm of the lever 70. In the short arm of the lever 70, is an adjustable screw 72 which bears against a ledge 74 at the under side of the arm 22. By this arrangement, the nozzle 34 is lifted at the completion of an operation as the flow of cement is shut off by closing the valve 50. A U-shaped space is provided between the lifted nozzle and a work-supporting roll 100 into which a piece of work may be moved laterally until its periphery rests against a gage roll 76 the periphery of which is beside the inner side of the nozzle 34. Since small quantities of cement sometimes accumulate at the nozzle outlets, it is better to have room so that the sole unit may be raised into contact with the end of the nozzle rather than pushing it laterally past the nozzle end and thereby wiping off any such accumulated cement upon the edge of the work. This gage roll 76 has a cylindrical rubber face extending below the nozzle and is mounted at the lower end of a vertical shaft 78 journaled in the arm 22 so that the roll has a fixed relation to the side of the nozzle. In order to make it easier for the operator to feed the work, the gage roll 76 is driven through countershafts 80 and 82 both of which are journaled in the tilting arm 22 and these above-mentioned shafts are interconnected by miter gears. Power may then be supplied to the shaft 82 from a vertical shaft 84 which is jour-

naled in the frame and is connected to the drive shaft 46 by a worm and gear 86. A connection between the vertical shaft 84 and the vertical countershaft 82 is effected by means of an extensible shaft 88 which includes universal joints, such as that shown at 90, so that the driving connection to the gage roll 76 is effective throughout the range of tilting movement of the nozzle-carrying arm 22.

By thus gaging the position of the applied stripe of coating material by means of a member which occupies a fixed position on the nozzle-carrying arm, it is possible to position the band of coating material just as desired regardless of the shape of the piece of work which is presented, by loosening set screw 92 and moving to right or left a rod 94 upon which a nozzle carrier 96 is clamped. Thus, if the combined platform sole and wedge heel has the shape of the work piece W, which is shown in Figs. 2 and 4, then, in coating the marginal portion of the under surface of this piece, it will be necessary to hold the work approximately in the position shown in Fig. 2 with the normally upper portion of the wedge heel extending outwardly beyond a vertical line through the gaging point G so that any attempt to gage the work from its then lower periphery would be unsuccessful. The particular style of work piece W, shown in Figs. 2 and 4, is squared at the rear end of its tread surface F, as indicated in the drawings, and it is desired to have the marginal band as close as possible to the periphery. After the coating applied to the tread surface F has dried sufficiently, the work is returned to the machine and a marginal band is applied to the attaching face A the rear end of which is curved or less sharply squared.

Another of the more unusual types of work is that shown in Fig. 5 where a work piece W' has a platform sole forepart S and a wedge heel H of a modified Louis type. On the under surface of the work piece W', the marginal band to be coated extends from the heel breast line B forward around the sole part S and back to the breast line on the other side.

It will be obvious that the problem of providing a suitable support for these pieces of work is rendered more difficult by the radical differences in thickness of the work between the foreparts and the heel ends thereof. The foreparts are of the order of one-quarter of an inch thick, whereas the heel ends are sometimes from two to three inches thick. Accordingly, there is provided a work-supporting roll 100 having corrugated disk portions 102, and this roll is mounted upon a shaft 104 journaled in a block 106 attached to the upper side of a plate 108 which is mounted upon the upper end of a flat slide 110. This slide is guided for vertical movement in a side recess 112 of a grooved, vertically elongated block 114 forming a part of an outward extension 116 of the frame 18. The slide is retained in this grooved block 114 by means of a cover plate 118, and upward movement of this slide is limited by an adjustable stop nut 120 threaded on a rod on the slide and which passes through a hole at the bottom of the block 114. Since the direction of movement of the work support 100 is thus parallel to the line of contact between the work and the gage roll 76, there is no tendency for such movement to change the relation of the work to the gage roll.

It is necessary or very desirable that the work-supporting roll 100 shall be held upwardly beneath the nozzle 34 with a tension which is uni-

form throughout its range of movement. To accomplish this by means of an ordinary helical wire spring coiled about a vertical axis, it would be necessary to provide a spring so long that it would extend nearly to the floor upon which the machine is positioned. It is possible, however, to give a substantially uniform lift throughout the three-inch range of movement of the slide by employing a tensioning device of the clock-spring type. Such a device embodies a flat, spiral spring 122 the outer end of which is secured to a stud 123 in a casing 128 rotatable upon a stud 130 carried by the frame extension 116. Around this casing is wound a cable 125 fastened at one end to the casing and at its other end to a pin 124 extending through a slot 126 in the grooved block 114 and fastened to the slide 110. The spring is then wound within the casing 128 and its inner end is attached to a stud 130 rotatable in the frame extension 116. To this stud, there is secured a ratchet 132, as shown in Fig. 1, and, when the proper tension has been imparted to the spring, the ratchet will be held in position by a pawl 134. A bill bolt 127 is provided to hold the stud 130 and its ratchet in the adjusted position.

Despite the changes in position of the work support, easy feeding of the work is effected by driving the roll-carrying shaft 104 through an extensible shaft 136 which is provided with universal joints, such as that at 138, and is driven from the vertical shaft 84 by means of miter gears 140. By this arrangement, no matter what the heightwise position of the work-supporting roll may be, its driving connection is unaffected.

In the operation of the machine, assuming that the treadle rod 62 is in raised position and that the various shafts are in rotation, a piece of work is moved laterally into the space between the nozzle and work support and then is lifted against the lower end of the depending nozzle 34 with its periphery against the gage roll 76. The treadle rod is then depressed to allow the arm 22 with the nozzle and gage roll to drop slightly, bringing the underside of the work against the work-supporting roll 100. The operator will then be able with ease to guide the work regardless of its shape so that the marginal portion of the upper surface of the work piece W is presented to the nozzle and a band of coating material is applied along the margin of the face F. Having in mind the shape of the piece of work as it is positioned in Fig. 2, and as the periphery of the work is traversed, the slide 110 carrying the work-supporting roll 100 moves up and down without binding and under a tension imparted by the spring 122 which is uniform throughout its range of movement. At the completion of the operation upon this particular margin, the treadle is released to the position shown in Fig. 1, thereupon shutting the valve 59 and raising the nozzle-carrying arm 22 through the levers 68 and 70 to separate it from the work-supporting roll and to facilitate the removal of the cemented piece of work.

Having thus described my invention, what I claim as new and desire to secure by Letters Patent of the United States is:

1. In a machine for coating sole-like shoe parts, a frame, a depressible work support, an arm pivoted on the frame, an applying member for coating the margin of the upper surface of such a shoe part, said applying member being carried

by said arm laterally of the pivot and above the work support thereby enabling the applying member to be moved toward and away from the work support and coacting with the work support to

5 provide a space into which a work piece may be moved laterally, and a gage carried on said pivoted arm beside said applying member and extending below it for contact with the periphery of said shoe part moved laterally thereagainst.

10 2. In a machine for coating shoe parts having a curved periphery and a radically varying thickness, an arm, an applying member thereon the lower side of which is arranged for contact with the upper surface of a piece of work presented

15 thereto, a cylindrical gage roll rotatably mounted on a vertical axis on said arm in fixed relation to and with its periphery beside said applying member to facilitate the application of a band of coating material to the margin of the upper side of

20 said shoe part, and a yieldingly mounted work support beneath said applying member to hold the work in engagement therewith, said support being guided for substantially vertical movement, the line of contact between the work and the periphery of the gage roll being parallel to the direction of movement of the work support.

25 3. In a machine for applying a band of coating material to the margin of a shoe part having a curved periphery and a radically varying thickness, a depending extruding nozzle, a driven gage roll rotatable with its periphery adjacent to the inner side of the nozzle engaging the periphery of the work to guide it, a work-supporting roll, a slide carrying said roll and guided for movement

30 vertically substantially beneath said nozzle to accommodate the variations in work thickness, a spring resisting downward movement of the slide, and means for driving said supporting roll irrespective of its heightwise relation to the machine.

40 4. In a machine for applying a band of cement to the margin of a shoe part, a depending nozzle, a pivoted arm supporting said nozzle for bodily heightwise displacement, a valve controlling the flow of cement to the nozzle carried by said arm, and an operator-controlled member for closing said valve and raising said arm.

45 5. In a machine for applying a band of cement to the margin of a shoe part, a depending coating applying member to the under side of which a piece of work may be presented, a work-supporting roll positioned beneath said applying member and rotatable about a substantially horizontal axis, a vertically sliding support in which said roll is journaled, means limiting the sliding movement of said support, and a spring exerting a substantially constant lifting force on said sliding support irrespective of the amount of displacement thereof.

50 6. In a machine for applying a band of coating material to the margin of a shoe part, a frame, a pivoted arm on said frame, a spring tending to hold said arm in depressed position, a nozzle carried on the outer end of the arm, a gage roll beside said nozzle rotatable on the arm about a vertical axis and capable of substantially vertical movement with the arm, a supporting roll beneath said nozzle, a vertically sliding member in which the latter roll is journaled, and means for driving both said gage roll and said supporting roll irrespective of the vertical movements of said rolls.

WILBUR L. MACKENZIE.
